CLAIM

The ornamental design for a adjustable distance tee-marker, as shown.

DESCRIPTION

FIG. 1 is a perspective view of an adjustable distance tee marker showing our new design;

FIG. 2 is a front elevation view thereof;

FIG. 3 is a right side elevation view thereof, the opposite side being a mirror image;

FIG. 4 is a rear elevation view thereof;

FIG. 5 is a top plan view thereof;

FIG. 6 is a bottom plan view thereof; and,

FIG. 7 is a perspective view of a second alternate embodiment, the corresponding views are similar to the first embodiment as disclosed in FIGS. 2-6 inclusive with the exception of the dimples.

The partial dimple pattern in FIGS. 2-6 is understood to cover the entire surface.
